SOCK LINING

Carlisle V. Watson, Auburn, Maine, assignor to
Henry G. Lumbard, Auburn, Maine

Application June 2, 1944, Serial No. 538,380

1 Claim. (Cl. 36—71)

1

This invention consists in a new and improved sock lining for shoes.

The shoemaking industry has struggled for years with the problem of providing a flexible sock lining that would lie flat in the bottom of a shoe provided with an upwardly projecting curved support or cookie for supporting the longitudinal arch of the foot. A sock lining which is initially flat invariably develops wrinkles when the attempt is made to give it the three dimensional contour required to fit smoothly upon an underlying insole having such an arch-supporting formation, and this is objectionable both from the standpoint of looks and comfort to the wearer. In the endeavor to avoid wrinkling, manufacturers have been driven to the use of sock linings of much lighter and thinner material than could otherwise be advantageously used in shoes.

I have discovered that these objections may be obviated and other shoemaking advantages obtained by providing a sock lining with a cookie insert piece larger in its area than the projected area which it is to cover in the inside shank curve of the sock lining and by securing such insert in the sock lining so as to throw a spring into it. As a result, the insert piece tends naturally to stand up in a convex curve while the body of the sock lining lies flat in a single plane or on the flatter surface of the shoe bottom.

Going more into detail, I propose to attach a cookie insert piece of the proper shape first at one end adjacent to the inside shank curvature of the sock lining, then swing the insert outwardly, thus throwing a spring into it, and finally securing the insert so that it is permanently retained with the spring included; that is to say, its natural position is stabilized in an upwardly inclined convex curve. I have thus, in effect, molded the inside shank portion of the sock lining into three dimensional contour and secured it permanently in that condition.

In practising the process of my invention under actual shoemaking conditions, I find that it is entirely practical so to shape the sock linings and the cookie insert piece that a single standard insert may be used for the sock linings for a full line of all sizes and widths in any selected style of shoe. In each instance the outline of the inside shank edge of the sock lining overlaps the adjacent edge of the cookie insert piece while the latter is secured to the sock lining by stitching or otherwise in a deformed or gathered condition which prevents the insert piece from lying flat.

The contour given the insert piece in the manner described provides a fullness which may be

2

utilized to enclose and cover a pad secured to the piece itself, or it may serve to cover a pad secured to the insole beneath it or to cover a convex extension or projection molded into the insole. My invention has thus a wide range of application depending in its details only on the preference of the shoemaker employing it.

These and other features of my invention will be best understood and appreciated from the following description of a preferred embodiment thereof selected for purposes of illustration and shown in the accompanying drawing, in which:

Fig. 1 is a plan view of the sock lining and insert piece in separated relation and right side up;

Fig. 2 is a fragmentary view showing the insert piece partially attached to the sock lining in inverted position;

Fig. 3 is a similar view showing the insert piece as fully attached, still in inverted position;

Fig. 4 is a fragmentary view showing a portion of the insert piece in attached relation and right side up; and

Fig. 5 is a similar fragmentary view showing a portion of a pad beneath the insert piece.

The sock lining 10 may be cut from calf upper leather or composite fibre or any flexible sheet material commonly used for sock linings. It is of conventional shape except that it has a reentrant concave recess in its inside shank edge extending from a rear point 11, herein shown as located slightly behind the heel breast line, to the forward point 12 located slightly behind the ball line. This recess is formed by removing material at this location from within the normal outline of the sock lining. This sock lining blank is normally flat and is represented in Fig. 1 with its grain side uppermost as it is eventually positioned in the shoe.

The insert blank 13 may be cut from the same material as the sock lining, or it may be of contrasting color, but preferably of substantially the same weight and texture as the body of the sock lining. The under surface of its inner edge is

skived at 14 as shown in Figs. 2 and 3. The curvature of its inner edge approximates that of the concave recess 11—12 of the sock lining blank and is shown as extending from a forward point 15 to a rear point 16. The outer edge of the insert 13 is also convex in outline and of somewhat sharper contour than the inner edge of the insert. As already noted I have found that a single standard insert 13 may be employed with a full assortment of sizes of sock linings since the sock linings may be prepared with a concave

recess 11-12 of predetermined outline in all sizes. The insert piece 13 is attached to the flat sock lining blank 10 in such a manner as to give it three-dimensional contour by first securing the forward end 15 of the insert to the margin of the recess 11-12 at the forward end thereof by a short line of tacking stitches 17. The relation of the two parts at this stage is well shown in Fig. 2 from which it will be noted that the rear end 16 of the insert piece 13 is thrown inwardly substantially within the contour of the sock lining. In this condition the inner edge of the insert piece overlaps the sock lining by a progressively increasing amount as the rear end of the insert is approached. Both pieces are shown in Fig. 2 flesh side uppermost or inverted in respect to the position in which the complete sock lining is to occupy in the finished shoe.

The next step in the process consists in forcibly swinging the insert piece outwardly to bring its rear end into the outline of the sock lining. The extent and direction of this swinging movement is indicated in Fig. 3, the dash line indicating the position of the insert 13 as it was originally attached by the tacking stitches. It will be understood that in swinging the insert piece in this manner its inner edge is forceably shortened and a spring or bulge is thrown into the body of the insert. In other words, the insert as a whole is confined to an area less than that which it would occupy in flat condition. The contour thus imparted to the insert is made permanent by extending the stitch line 17 completely along the marginal edge of the concave recess 11-12. The inner skived edge 14 of the insert piece extends inwardly and underlies the body of the sock lining. Preferably the stitching is done with the sock lining right side up so that the stitch line 17 may be gauged from the marginal edge of the recess 11-12 and lie parallel to it. The upwardly convex-curvature of the insert piece 13 is well shown in Fig. 4 which shows the composite sock lining in cross-section.

The composite sock lining with its insert 13 molded or shaped as above described may now be placed in a shoe having a longitudinal arch-support, and the insert will conform smoothly to the convexity of the support while the body of the sock lining lies smoothly and without wrinkling on the insole. This is so because the nar-

row section of the sock lining which remains in the shank after cutting the concave recess therein is called upon to flex in longitudinal direction only in conforming to the underlying insole, while the insert 13 must follow the double curvature which is required in conforming naturally to the transverse curvature of the inside shank portion of the insole.

If desired my invention may be carried one step further by including in the insert 13, or attaching to its lower surface, a shank supporting pad 18 of rubber or other resilient composition. In this way a sock lining is made available which includes an arch-supporting member and which may be employed to impart this characteristic to the shoe without requiring any special conformation of the sole itself or the provision of an arch-supporting cookie in the structure of the shoe bottom.

While I have herein shown the insert 13 as being attached by a line of stitching, an adhesive union of the parts is satisfactory in many instances.

Having thus disclosed my invention and described in detail an illustrative embodiment thereof, I claim as new and desire to secure by Letters Patent:

An improved form fitting sock lining for a shoe having an insole presenting both longitudinal curvature and convex curvature at its inside shank portion for supporting the arch of the foot, said sock lining having a body of flexible material and the contour of the insole modified by having a deep reentrant concave recess in its inside shank edge extending from approximately the heel breast line to the ball line and providing clearance for the transversely convexed portion of the underlying insole, and a cookie insert piece of substantially the same flexible material as the sock lining having a convex inner edge of greater overall length than said recess and being secured to the sock lining within the concave margin of the recess and along a line of sharper curvature than the normal flat curvature of the edge of the recess, thereby forming an upward bulge of convex curvature in the insert piece covering said recess while the body of the sock lining conforms without wrinkles to the underlying surface of the longitudinally and transversely curved insole.
